UNITED STATES PATENT OFFICE.

FRANCIS B. BURNS, OF NORTH RIVER, NEW YORK.

GRAVITY SEPARATOR FOR GARNET ORES.

Application filed April 27, 1926. Serial No. 104,994.

This invention relates to ore separators of that character wherein a jiggling screen is disposed within a hutch and the general object of the present invention is to provide a 5 separator of this character which is particularly adapted for the separation of garnets from crushed ore.

Another object is to provide a separator of this character having a screen disposed within 10 a hutch and upon which screen the ore is discharged and provide means whereby the screen may be given an oscillating motion in a vertical plane within the hutch and also whereby the screen may be inclined laterally to cause a compound motion to be given 15 to the screen.

A further object is to provide means at the end of the screen whereby the tailings may be permitted to pass and the relatively 20 coarse rock and garnets are held from passage with the tailings or, in other words, held upon the screen while the fines pass down through the screen.

Still another object is to support the pivotal end of the screen upon bearings which 25 will permit the vertical oscillation of the screen but which may be also adjusted to cant the screen at an angle sidewise.

Other objects will appear in the course of 30 the following description.

My invention is illustrated in the accompanying drawings wherein:—

Figure 1 is a front elevation of a separator constructed in accordance with my invention, one side of the separator being in 35 section;

Fig. 2 is a top plan view of the separator;

Fig. 3 is a section on the line 3—3 of Figure 2;

Fig. 4 is a fragmentary vertical section on the line 4—4 of Figure 3.

Referring to these drawings 10 designates a tank, which, as illustrated, is divided into two portions or hutes 11 by a vertical partition 12. I do not wish to be limited to this, however, inasmuch as I have only provided this construction so as to economize in room and permit two screening devices to be disposed side by side. The bottom 13 of each 45 hutch 11 extends horizontally from the partition 12 and then extends upward and outward and this upwardly and outwardly extending portion or wall is provided with a discharge opening or gate 14.

Extending upward from the rear wall of the tank 10 are brackets 15 which support

a driving shaft 16 carrying a pulley 17 whereby power may be transmitted to it. Mounted upon the shaft 16 are eccentrics 18 having the usual two-part eccentric straps 60 19 from which depend the screen supporting rods 20 having their upper ends screw-threaded for engagement in the straps and carrying the nuts 21.

Disposed in each hutch is a screen consisting of the rear transversely extending member 22 and the two longitudinally extending parallel members 23, these members 22 and 23 constituting a rectangular frame which is open at one end. The rods 20 have 70 screw-threaded engagement at their lower ends with the end member 22 so that this end member may be adjusted up or down upon the rods and the screen is held in its adjusted position by means of the nuts 21. The bottom of the screen frame is formed by the finely meshed screen 24, held in place by strips 25, these in turn being held to the side members 23 by the clips 26, as shown in Figure 1.

The front wall 27 of each hutch is cut away as at 28 opposite the end of each screen, this cut away portion being larger than the cross sectional area of the screen and attached in any suitable manner to the edge 85 or margin of this cut away margin is a flexible gasket 29, as it may be termed, which is likewise cut away to form a rectangular opening approximately equal to the screen opening and this free end or margin is attached to the screen frame.

The tail end of the screen is supported by means of the shaft 30 passing through bearings 31 which in turn are mounted upon the side walls of the screen. One end of this 95 shaft 30 is disposed within a bracket 32 mounted upon the outside wall of the hutch. This bracket has a recess 33 in the upper face within which the squared end of the shaft 30 is disposed. One wall of each 100 bracket is formed with a vertically extending slot 34 and an adjusting screw 35 constituting a clamp passes through this slot and is screwed into engagement with the squared end of the shaft 30.

Extending vertically through the shaft 30 is an adjusting screw 36 which bears against the floor of the recess 33 and thus it will be seen that as this screw 36 is turned, the other end of the shaft 30 may be raised or lowered 110 a slight amount and that the shaft may be thus disposed at an inclination to a hori-

zontal plane. The opposite end of the shaft 30 is pivotally mounted within a bracket 37 which is longitudinally recessed to receive the squared end 38 of the shaft and a pivot bolt 39 or like member passes through the side wall of the recess and through this squared end so that the shaft 30 at one end is pivotally mounted and at the other end is vertically adjustable.

Disposed at the tail or discharge end of the screen is an overflow gate or dam designated 40. This has a downwardly and forwardly inclined upper face which contacts with the screen frame at its forward edge. The rear end of this gate or dam extends downward as at 41, into contact with the screen. Extending across the screen frame and resting upon the side members thereof is a cross bar 42 and passing upward through the overflow gate 40 are bolts 43 which pass through the cross bar and carry the nuts 44. By this means the overflow gate or dam may be adjusted to raise or lower it.

The crushed ore is fed onto the screen from a storage bin by means of a spout 45 or any other suitable means to this end, and discharged upon the screen about the middle thereof. The water tank of each hutch must have a continuous flow of water passing through it and keeping it filled to a suitable height with relation to the screen. The eccentric shaft 16 is driven at from 280 to 320 R. P. M., and this causes a jiggling motion of the screen frame. The jiggling motion of the screen under the action of water causes the finer particles of ore to pass through the screen. The refuse or tailings are discharged over the overflow dam or gate while the oversize collects in the front end of the screen frame in a quantity large enough to be shoveled out at intervals. The very fine particles which pass through the screen into the hutch settle in the bottom thereof and are discharged through the discharge gate 45 and from thence pass to another separator preferably of the same character as the one just described which, however, has a finer meshed screen. It will require about four machines in a row, each screen being finer than the one in advance, in order to secure a proper clean-up of the material.

Both of the eccentrics may be set at the same angle and have the same throw and move precisely together. By adjusting the rods 20 the screen may be raised or lowered. By adjusting the shaft 30 and by properly adjusting the rods 20 so as to lengthen one with respect to the other, the screen may be readily leveled by means of the screw 36.

While I have illustrated a construction which I have found to be particularly effective, I do not wish to be limited thereto as it is obvious that many changes might be made therein without departing from the spirit

of the invention as defined in the appended claims.

It will be noted that the screen has a jiggling motion at its head end, that is the end toward the eccentric and that at the tail end the screen has a certain amount of longitudinal movement of small dimensions. This is for the reason that the tail end of the screen is swingingly mounted on the gears 31 so that as the rear end or head end of the screen rises and falls, the forward end of the screen will swing backward and forward. Thus, when the head end jiggles up and down, the screen will be moved slightly endwise. This motion is very important in moving garnets toward the head or jiggling end of the separator. When the separator is in operation, the head end is always elevated above the tail end. The coarse ore requires more tilt than finer ores and thus by adjusting the rods 20, the proper elevation of the screen can be maintained, as conditions change with the ore. By adjusting one of the rods 20 to the inclination of shaft 30, the screen can always be kept level crosswise and this may be done without stopping the machine or feed by backing off the nut on top of the screen and following up with the nut on the bottom of the screen. This, of course, accounts for efficiency.

The cap screw 35 is designed to hold the shaft 30 rigidly against the wall or bracket 32 after adjustments have been made.

The adjustment of the shaft 30 by means of the screw 36 is a very important feature of my invention in that the bearings 31 must be babbited or bronze lined and will soon wear enough to let the screen out of level. This ordinarily would mean that the machine would have to be shut down and screen leveled up and bearings re-babbited or re-lined, the operation taking about five hours. With the shaft 30 pivoted at one end and adjustable at the other end and two cams with their rods 20 supporting the other end of the screen, the screen frame cannot always be kept level crosswise and the machine may be constantly adjusted to secure this level by letting one end of the shaft 30 down or raising it and by correspondingly adjusting one of the eccentric rods, and thus the screen may be leveled without stopping the machine or stopping the feed, this operation only requiring one or two minutes. To secure a proper separation of the garnets from the garnet ore it is particularly important that the screen be level transversely.

It is to be particularly noted that this machine does not operate automatically as an automatic separation with garnetore is impracticable for the reason that rock carrying garnet deposit is from eighty-five per cent to eighty-eight per cent as heavy as the clear garnets and this makes a very

- difficult ore to separate. With automatic separators, after they are adjusted to the proper point of separation, this adjustment must be maintained, as if it is not maintained, there is liability of getting dirty concentrates and loose garnets in the tailings, thus causing a low recovery. In other words, after adjusting an automatic separator, the feed must run even, the ore must run uniform in quality, and the water must be uniform in amount. It is impossible to secure these prerequisites in concentrating garnet ores. While my garnet separator will make a clean concentrate and discharge a clean tailing, the concentrates have to be shoveled out of the screen at intervals according to the amount of ore being treated and conditions can fluctuate to a wide range without affecting the separation. This is due to the fact that the machine does not work automatically but permits the concentrates to be shoveled out of the front end at intervals according to the amount of ore being treated. In my machine the concentrates are gathered at the rear of the screen, that is, close to the rear cross bar 22, the middlings gathered slightly forward of the feed spout, while the tailings are discharged over the gate 40.
- 30 My separator is particularly adapted to garnet bearing ores because it has secured in actual practice, a 95% recovery, making a clean concentrate and discharging a clear tailing. The separator has a relatively large capacity under varying conditions and this is particularly necessary owing to the small margin in weight between garnet concentrates and garnet bearing ores.
- I claim:—
- 49 1. An ore separator of the character described including a tank having a discharge gate in its bottom, a screen frame open at one end and carrying a screen, the open end of the screen discharging through an end wall of the tank, power operated means for giving vertical oscillation to the tank, and including two vertically reciprocable rods connected to that end of the screen remote from its discharge end, the screen being connected to each rod for vertical adjustment, a transversely extending horizontal support for the discharge end of the screen pivotally mounted at one end and means for vertically adjusting the other end of the pivotal support to thereby adjust the screen in a vertical plane.
- 50 2. An ore separator of the character described including a tank, a screen therein including a screen frame open at one end and a screen attached to the bottom of the screen frame, the open end of the screen frame being flexibly connected to the end wall of the tank, a shaft disposed above the rear end of the screen and carrying eccentrics, eccentric straps mounted thereon, adjustable rods connecting said straps to the rear end of the screen frame, each of said rods being adjustable independently of the other, and means for pivotally supporting the forward end of the screen including a shaft, hangers mounted thereon and engaging the forward end of the screen frame, and means for pivotally supporting one end of the shaft, and vertically adjustable means for supporting the other end of the shaft.
- 55 3. An ore separator of the character described including a tank, a screen therein including a screen frame open at one end and a screen attached to the bottom of the screen frame being flexibly connected to the end wall of the tank, a shaft disposed above the rear end of the screen and carrying eccentrics, eccentric straps mounted thereon, adjustable rods connecting said straps to the rear end of the screen frame, each of said rods being adjustable independently of the other, and means for pivotally supporting the forward end of the screen including a shaft, hangers mounted thereon and engaging the forward end of the screen frame, and means for pivotally supporting one end of the shaft, and vertically adjustable means for supporting the other end of the shaft.
- 60 4. A garnet ore separator including a tank, a screen frame open at one end and carrying a screen, the open end of the screen being flexibly connected to the end wall of the tank, a transverse shaft mounted upon the end wall of the tank above the screen and pivotally supported at one end, hangers attached to the discharge end of the screen and swingingly engaging said shaft, means for adjusting the angle of the shaft to a horizontal plane, power operated means for causing vertical oscillation of the head end of the screen and including means whereby the screen may be adjusted into parallel relation to the shaft.

In testimony whereof I hereunto affix my signature.

FRANCIS B. BURNS.
